UNITED STATES PATENT OFFICE.

WALTER MUIR REEVES, OF LOS ANGELES, CALIFORNIA.

EVAPORATIVE COOLER.

1,086,219.

Specification of Letters Patent.

Patented Feb. 3, 1914.

Application filed February 12, 1912. Serial No. 677,038.

To all whom it may concern:

Be it known that I, WALTER M. REEVES, a citizen of the United States, residing at Los Angeles, in the county of Los Angeles and State of California, have invented a new and useful Improvement in Evaporative Coolers, of which the following is a specification.

My invention relates to refrigerators designed to cool their contents without the use 10 of ice.

My object is to so arrange a refrigerator box or cooler as to produce a sufficient degree of frigidity by means of the rapid evaporation of running water, and I attain 15 this object by means of the apparatus illustrated in the accompanying drawings, in which—

Figure 1 is a vertical sectional view of my cooler on the line $x'-x'$ Figs. 2 and 5. Fig. 20 2 is a horizontal sectional view on the line x^2-x^2 Fig. 1 looking upward with a portion of the top and water-table broken away. Fig. 3 is a front view with a portion of the door broken away to show the interior. Fig. 25 4 is a plan view of the top water table. Fig. 5 is a horizontal sectional view of the base on the line x^5-x^5 Fig. 1.

In Fig. 1, 1 and 2 are the outer sides of the cooler, 3 the top, 4 the bottom, 5 and 6 30 inner side walls, 7 the water table, 8 the water reservoir, 9 reservoir cover, 10 outlet of reservoir, 10' legs on reservoir, 11 filter, 12 orifice in top of cooler, 13 shoulder in top, 14 saucer in the water table, 15 and 16 feed 35 channels in water table, 15' and 17 outlet holes in water table, 18 grooves in water table, 19 air inlets in sides, 20 cool air inlets in inner walls, 21 warm air outlet, 22 and 23 drip channels in base, 24, 25, 26 and 27 grooves in base, 28 drip outlets in base, 29 carriage for cooler, 30 drip outlet in carriage, 31 rollers on carriage, 32 shelf ledges on inner wall, 33 shelves, 34 and 35 bolts, 36 air and drip chamber, 37 water chamber, 40 45 38 drain pan.

Similar reference characters refer to the same parts in the other figures, and in Fig. 2, 39 is the rear outer wall and 40 the rear inner wall.

50 In Fig. 3, 41 is the front wall, 42 the door opening, and 43 the door.

My cooler, or refrigerator, is designed to operate by means of air cooled in transmission from the atmosphere to the inner chamber of the cooler, by causing it to pass over or through slowly dripping water, which it

evaporates; and at the same time providing an outlet into the atmosphere for the warm air from the inner chamber.

I construct my cooler entirely of pottery 60 or earthen ware slabs, which are porous with the exception of one of their faces which is glazed, the glazed faces being toward the food contents, and upon the outside of the cooler and the porous faces exposed to the 65 water and air, thus making the cooler sanitary and securing effective evaporation for cooling the air.

In constructing the cooler I use the pottery base 4 with its outer face glazed and 70 its inner face porous, and having formed in its inner face the double grooves 24 and 25 and 26 and 27 with the drain channels 22 and 23 therebetween and the small drainage holes 28 leading from the grooves and 75 the channel to the outer air. These grooves, channels, and holes are formed on the two sides and the back, and on the front there is but one groove formed and no drainage channel or outlets. In the grooves 24 and 80 27 I set the side slabs 2 and 1 with their glazed faces outward, and in the grooves 25 and 26 I set the wall slabs 5 and 6 with their glazed faces inward and their porous faces outward facing the outer slabs leaving between the outside and inside slabs the chamber 36. The back of the cooler is set 85 in the same manner. The porous walls of the chamber 36 may be flat, or they may be corrugated or stepped as shown in the drawing, in order to afford a larger evaporating surface. The corrugations or steps may face each other or be arranged alternately as shown in the drawing. The front slab 41 is glazed on both sides and has a door 90 95 opening 42 in it and the door 43 made similar to the side hung in the opening. The top slab of pottery 3 has formed around its edges on the porous face the shoulder 13 adapted to fit the top edge of the side slabs 100 and in its center is formed the orifice 12. The inner walls 5 and 6 and the back inner wall 40 are shorter than the outer walls and are capped with the water table 7 which has formed on its glazed face the grooves 105 18 to fit the top of the side walls 5 and 6, and the rear wall 40. In the center of the top of the water table 7 is formed the shallow cup shaped depression 14 from which radiate the water channels 15 and 16 toward 110 the side and back, half of which extend to the edge of the table and the other half

to within an inch, more or less, of the edge, to holes through the table opening at the porous face of the inner walls, being so arranged in alternate order. The face of the 5 water-table slants slightly downward from the center to the edge, and the radial water channels have a similar slant. The outer edge of the water-table is slightly beveled downward, and the channels that extend to 10 the edge follow this bevel. The holes 15' in the back, however, are larger so as to act as air inlets. The edge of the water table fits loosely the face of the outer walls and allows the water to ooze over the edge and 15 down the porous inner face of said walls. The inner walls 5 and 6 have formed on their inner faces the shelf ledges 32 on which may be placed the perforated shelves 33. These walls have also near their bottom 20 the large openings 20 through which the cooled air enters the inner chamber. Having thus assembled the parts I clamp them securely in position by means of the bolts 34 and 35 and then set it in the carriage 29 provided with the drip outlet 30 and the rollers 31. On top of the cooler I place the water reservoir 8 provided with the central conical outlet 10, the filter 11, and the cover 9. This reservoir is also made of 25 pottery and has the legs 10' which allow an air space between it and the top of the cooler. The orifice 12 is larger than the cone 10 and allows the passage of air into the top of the cooler whence it passes over 30 the water table and down through the inlets 15'.

In operation the water will filter from the reservoir 8 through the outlet 10 and drop into the cup 14 which as it overflows will 40 pass the water through the channels 15 and 16 thus distributing it equally to the three sides of the cooler and allow it to drain equally through the holes 15' and 17 and over the edge of the water table down the 45 porous faces of both walls of the air chamber. The air will be admitted through the air inlets 12 and 19 and passing down the

air chamber will evaporate the water and thus become cooled and then pass through the openings 20 into the inner chamber, 50 forcing the warm air out of the chamber through the outlets 21.

Having thus described my cooler, what I claim as my invention and desire Letters Patent for, is—

1. An evaporative cooler, comprising detachable spaced inner and outer walls top and base of porous stone or similar substance the inner faces of the inner walls and the outer faces of the outer walls being 60 glazed and the adjacent faces of the walls being left porous, providing air and water chambers between the walls, air inlets and outlets, water inlets and outlets, a radially grooved water table on the top of the cooler 65 communicating with the chamber, a water reservoir communicating with the water table, a food chamber inclosed by the walls and means to connect the same with the air chambers.

2. In an evaporative cooler, the combination of detachable, spaced inner and outer walls, top and base of a porous substance, the inner faces of the inner walls and the outer faces of the outer walls being glazed 75 and the adjacent faces being porous, air and water chambers between the walls, a radially grooved water table on the top of the inner walls communicating with the chambers, a water reservoir communicating with said 80 water table, a food chamber inclosed by said walls, means for the admission of cool air and the emission of warm air from said chamber, means for the supply of water from said reservoir to said water table, 85 water passages through said water table, means for the absorption of water by the inner and outer walls, and means for draining the surplus water.
